RAILWAY CAR END

Ellis W. Test, Hinsdale, Ill., and William H. Mussey, deceased, late of Chicago, Ill., by Carrie S. Mussey, executrix, Chicago, Ill., assignors to Pullman-Standard Car Manufacturing Company, Chicago, Ill., a corporation of Delaware

Application January 4, 1940, Serial No. 312,372

13 Claims. (Cl. 105—410)

The invention relates to railway box cars and has for its primary object the provision of corrugated end walls therefor reinforced to afford uniform deflection thereof under load.

The principal object of the invention is the provision of a corrugated car end reinforced in localized areas at the points of greatest deflection to prevent distortion of the end by low shifting loads concentrated at the center and to strengthen the end at the center where it is weakest.

An important object of the invention is the provision of a car end reinforced at the points of greatest flexure to provide more uniform deflection without disturbing the inherent flexibility of the end. Specifically, the invention contemplates a corrugated car end in which reinforcing gusset plates are disposed in alternating corrugations with intervening corrugations free of such reinforcing gussets to provide an area of flexibility separating the corrugations reinforced. The invention also proposes the disposition of such gusset plates in spaced relation to the valleys of their respective corrugations.

Further, the invention involves the use of reinforcing gusset plates disposed between the lowermost corrugation of a corrugated end wall and the car center sill to brace the corrugation and prevent distortion thereof.

The invention comprehends the placement of reinforcing gusset plates between corrugations in the lowermost area of a car end at the center thereof, at opposite sides of the center in the plane of brace plates between the lowermost corrugation and the center sill, and at the center of the end in combination with others disposed at opposite sides of the center, or disposed merely at opposite sides of the center of the end.

The foregoing and other objects are attained by the arrangement illustrated in the accompanying drawings, in which—

Fig. 1 is a general perspective view of a car end constructed in accordance with the invention and showing the reinforcing gusset plates in the center of the end disposed between alternate corrugations with the brace plates arranged between the lowermost corrugation and the center sill in the plane of the side webs of the center sill;

Fig. 2 is a sectional view taken on the line 2—2 of Fig. 1 illustrating the securement, by welding, of one of the reinforcing gusset plates within a corrugation;

Fig. 3 is a vertical, sectional view taken on the line 3—3 of Fig. 1 showing the disposition of reinforcing gusset plates in alternate corruga-

tions on the outer side of the end and brace plates between the lowermost corrugation and the center sill;

Fig. 4 is a transverse, sectional view taken on the line 4—4 of Fig. 3 through the brace plates showing their attachment to the center sill and end wall by welding;

Fig. 5 is a view similar to Fig. 3 of a modified form of the invention in which the reinforcing gusset plates are disposed on the inner side of the end wall in alternate corrugations;

Fig. 6 is a similar view of another modification in which the reinforcing gusset plates are disposed in alternate corrugations on the outer side of the end wall in spaced relation to the valleys of the corrugations;

Fig. 7 is a perspective view of the lowermost portion of a corrugated end embodying a modified arrangement of the invention in that the reinforcing gusset plates are disposed in alternate corrugations at opposite sides of the center of the end in the plane of the brace plates at the center sill position; and

Fig. 8 is an end view of the lowermost portion of an end embodying a still further modified form of the invention in which the reinforcing gusset plates are disposed between alternate corrugations in the center of the end and at opposite sides of the center.

In the drawings, 10 represents a car end having a plurality of parallel, horizontally disposed corrugations 11 extending across the end substantially throughout its full height. The end is comprised of upper and lower sections 12 and 13 joined by a horizontal welded seam 14 and provided with marginal flanges 15 for attachment to the car sides 16 having side sills 17 and side plates 18. End plate 19 connects the side plates 18, and roof sheets 21 overlap both and are secured by welding. An end sill 20 connects the side sills 17 and forms the bottom means of attachment for the end wall which is secured thereto by welding. Center sill 32, having a top 22 and spaced vertical side webs 23, projects beyond the plane of the end wall and is traversed by the end sill 20 which is welded to the top 22. A built-up, welded striking casting 24 is welded in place on the end of the center sill and is adapted to receive and support a coupler shank (not shown). The corrugations 11, as shown, are disposed outwardly of the general plane of the end wall and taper at their opposite ends flush therewith, as at 25, although they may be disposed inwardly of the plane of the end wall without departing from

the invention. The corrugations each have a crest, or crown, 26 and side walls 27 and provide intervening valleys 28 which are utilized for a purpose hereinafter to appear. On the inner side of the end wall, nailing strips 29 are disposed in the corrugations 11 and to which a wooden lining 30 is secured which extends from the wooden floor 31 to a point above the highest load line.

Brace plates 35 are disposed between the lowermost corrugation 11 and the top 22 of the center sill and, as best shown in Fig. 4, are disposed substantially in the plane of the side webs 23 and are adapted to prevent distortion of the bottom corrugation at the center under the effect of a low shifting load concentrated at the center of the car end. It has been determined, by test, that this effect, to which all ends are subject, has been very materially reduced by the use of these reinforcements; and, to all practical purposes, the tendency toward this type of distortion has been eliminated. The brace plates 35 at the bottom where they are attached to the center sill top 22 are flanged inwardly at 36 and secured by arc welding. The remaining edges of the brace plates are flanged outwardly, as at 37, and are spot-welded to the vertical flange of the end sill 20, the lower side wall 27 of the bottom corrugation 11 and the intervening flat portion of the end 10. At the opposite or upper side of the bottom corrugation 11, a reinforcing gusset plate 40 is disposed at the center of the car end in the valley 28 between the side walls 27 of adjacent corrugations to which and the valley 28 it is secured at the edges by arc welding, as best shown in Fig. 2. Similar gusset plates 40 are disposed in each valley 28 between adjoining corrugations 11 up to a point midway of the height of the end 10—the uppermost reinforcing gusset 40 bridging the welded seam 14 joining the upper and lower sections 12 and 13 of the end wall.

Considering each undulation of the end wall as a corrugation, the reinforcing gusset plates are disposed in alternate corrugations, whereby the reinforcing gussets are discontinuous and corrugations free of such reinforcing gussets are interposed in order to provide areas of flexibility separating the corrugations reinforced. As the normal tendency of the end wall, under load, is to bow outwardly, whereby the valleys 28 between corrugations and the corrugations themselves, both inside and outside of the end wall, tend to spread, the reinforcing gusset plates therefore function in tension between the various corrugations to prevent distortion thereof. The reinforcing gusset plates 40 are of less height than the depth of the corrugations and are arranged with their outermost edges in planes inside of the planes of the crests of the corrugations in order fully to take advantage of the interposed areas of flexibility between corrugations reinforced and permit a slight flexing of the metal in the side walls of adjacent corrugations under stress. The reinforcing gusset plates operate to prevent excessive spread of the corrugations at points of greatest bending of the end wall under thrusts of the load, and, thus restrained, the corrugations retain their resiliency, short of a permanent set, under stress. The effect of the reinforcing gusset plates is to increase the strength of the end wall at the point where, normally, it is weakest; and test results have indicated not only a more uniform deflection of the end wall by the use of such

reinforcements but that the stresses produced in the end wall under the same pressure are greatly lessened thereby in comparison with ends not equipped therewith.

5 The modified arrangement illustrated in Fig. 5 is similar in construction to that above described, but the reinforcing gusset plates 40 are disposed on the inner side of the end wall 10 and are welded in the same manner and relation as when used on the outer side and function in tension between the corrugation side walls 27, under load, to prevent excessive spread of the corrugations while affording the slight flexibility achieved by the disposition of the reinforcing 15 gussets in alternate corrugations and of less height than the depth of the corrugations, as in the first form, and no further description is thought to be necessary.

10 The modified construction illustrated in Fig. 6 corresponds exactly with that shown in Fig. 3, and above described, except for the fact that the reinforcing gusset plates 40 are disposed directly in tension between the corrugation side walls 27 in spaced relation to the valleys 28, as at 41, and are connected only to the side walls of adjacent 15 corrugations and not to the floor of the intervening valley 28 to avoid possible distortion of the corrugation walls under thrust of the load.

15 The modified arrangement illustrated in Fig. 7 20 corresponds exactly with that shown in Fig. 3, and above described, except for the fact that the reinforcing gusset plates 40 are disposed directly in tension between the corrugation side walls 27 in spaced relation to the valleys 28, as at 41, and are connected only to the side walls of adjacent 25 corrugations and not to the floor of the intervening valley 28 to avoid possible distortion of the corrugation walls under thrust of the load.

20 The modified arrangement illustrated in Fig. 8 25 corresponds exactly with that shown in Fig. 3, and above described, except for the fact that the reinforcing gusset plates 40 are disposed directly in tension between the corrugation side walls 27 in spaced relation to the valleys 28, as at 41, and are connected only to the side walls of adjacent 30 corrugations and not to the floor of the intervening valley 28 to avoid possible distortion of the corrugation walls under thrust of the load.

30 What is claimed is:

35 1. In a railway car having a center sill provided with side webs and a top, an end sill traversing the top of the center sill, an end wall surmounting said end sill and having a plurality of horizontal corrugations disposed in parallel relation with intervening valleys substantially throughout the full height of said end wall, and separate gusset members disposed substantially in the plane of said side webs and connecting said center sill, end sill and the lowermost of said corrugations and integrally secured therewith.

40 2. In a railway car having a center sill provided with side webs and a top, an end sill traversing the top of the center sill, an end wall surmounting said end sill and having a plurality of horizontal corrugations disposed in parallel relation with intervening valleys substantially throughout the full height of said end wall, gusset members disposed substantially in the plane of said side webs and connecting said center sill, end sill and the lowermost of said corrugations

and integrally secured therewith, and reinforcing members located laterally of the center of said wall between adjoining corrugations in the lowermost area of the end wall adapted to be disposed in tension when the end wall is under load and arranged substantially in the plane of said gussets.

3. In a railway car having a center sill provided with side webs and a top, an end sill traversing the top of the center sill, an end wall surmounting said end sill and having a plurality of horizontal corrugations disposed in parallel relation with intervening valleys substantially throughout the full height of said end wall, gusset members disposed substantially in the plane of said side webs and connecting said center sill, end sill and the lowermost of said corrugations and integrally secured therewith, and reinforcing members in the center of said wall between adjoining corrugations in the lowermost area of the end wall adapted to be disposed in tension when the end wall is under load.

4. In a railway car having a center sill provided with side webs and a top, an end sill traversing the top of the center sill, an end wall surmounting said end sill and having a plurality of horizontal corrugations disposed in parallel relation with intervening valleys substantially throughout the full height of said end wall, gusset members disposed substantially in the plane of said side webs and connecting said center sill, end sill and the lowermost of said corrugations and integrally secured therewith, and reinforcing members in the center of said wall and other members located laterally of the center thereof between adjoining corrugations in the lowermost area of the end wall adapted to be disposed in tension when the end wall is under load.

5. In a railway car having a center sill provided with side webs and a top, an end sill traversing the top of the center sill, an end wall surmounting said end sill and having a plurality of horizontal corrugations disposed in parallel relation with intervening valleys substantially throughout the full height of said end wall, gusset members disposed substantially in the plane of said side webs and connecting said center sill, end sill and the lowermost of said corrugations and integrally secured therewith, and reinforcing members located laterally of the center of said wall between adjoining corrugations in the lowermost area of the end wall and arranged substantially in the plane of said gussets and spaced from the lowermost part of the said valleys adapted to be disposed in tension when the end wall is under load.

6. In a railway car having a center sill provided with side webs and a top, an end sill traversing the top of the center sill, an end wall surmounting said end sill and having a plurality of horizontal corrugations disposed in parallel relation with intervening valleys substantially throughout the full height of said end wall, gusset members disposed substantially in the plane of said side webs and connecting said center sill, end sill and the lowermost of said corrugations and integrally secured therewith, and reinforcing members in the center of said wall between adjoining corrugations in the lowermost area of the end wall and spaced from the lowermost part of the said valleys adapted to be disposed in tension when the end wall is under load.

7. In a railway car having a center sill provided with side webs and a top, an end sill traversing the top of the center sill, an end wall sur-

mounting said end sill and having a plurality of horizontal corrugations disposed in parallel relation with intervening valleys substantially throughout the full height of said end wall, gusset members disposed substantially in the plane of said side webs and connecting said center sill, end sill and the lowermost of said corrugations and integrally secured therewith, and reinforcing members in the center of said wall and other members located laterally of the center thereof between adjoining corrugations in the lowermost area of the end wall and spaced from the lowermost part of the said valleys.

8. In a railway car having a center sill provided with side webs and a top, an end sill traversing the top of the center sill, an end wall surmounting said end sill and having a plurality of horizontal corrugations disposed in parallel relation with intervening valleys substantially throughout the full height of said end wall, and separate flanged gusset members disposed substantially in the plane of said side webs and connecting said center sill, end sill and the lowermost of said corrugations and integrally secured therewith.

9. In a railway car end wall comprised of a plurality of panels secured by a horizontal joint at their adjoining edges, each of said panels having a plurality of horizontal corrugations extending in parallel relation, vertically extending reinforcing members between certain of said corrugations adapted to be disposed in tension when the end wall is under load and at least one of said members being integrally connected to the adjacent sides of the corrugations on each side of said joint.

10. In a railway car having a center sill provided with a top portion, an end sill traversing the top portions of the center sill, an end wall surmounting said end sill and having a plurality of horizontal corrugations disposed in parallel relation with intervening valleys, gusset means disposed between the lowermost of said corrugations and the center sill and connecting said corrugation, end sill, and center sill and integrally secured therewith, and reinforcing members in the center of said wall between adjoining corrugations in the lowermost area of the end wall adapted to be disposed in tension when the end wall is under load.

11. In a railway car, an end wall including a plurality of horizontal corrugations disposed in parallel relation substantially throughout the major height of the end wall and located wholly to one side of the main plane of the end wall, and a series of substantially vertically aligned, separate, discontinuous, vertically extending reinforcing members located laterally of the center of the wall secured to and connecting the adjacent sides of adjoining corrugations in the lowermost area of the wall adapted to be stressed in tension when the end wall is under load, said reinforcing members being disposed on one side only of the end wall and on the same side of said main plane as the corrugations whereby excessive spread of the said adjoining corrugations is prevented and flexibility in the corrugated end wall is retained.

12. In a railway car, an end wall including a plurality of horizontal corrugations disposed in parallel relation with intervening valleys substantially throughout the major height of the end wall, and a series of substantially vertically aligned, separate, discontinuous, vertically extending reinforcing members located laterally of

the center of the wall secured to and connecting the adjacent sides of adjoining corrugations in the lowermost area of the end wall adapted to be stressed in tension when the wall is under load and spaced from the lowermost part of said valleys, said reinforcing members being disposed on one side only of the end wall whereby excessive spread of the said adjoining corrugations is prevented and flexibility in the corrugated end wall is retained.

13. In a railway car, an end wall including a plurality of horizontal corrugations disposed in parallel relation substantially throughout the

major height of the end wall, and a series of substantially vertically aligned, vertically extending separate reinforcing members arranged discontinuously on one side only of the end wall and secured to and connecting the adjacent sides of certain adjoining corrugations and adapted to be stressed in tension, and thereby prevent excessive spread of the said adjoining corrugations, when the end wall is under load.
